UNITED STATES PATENT OFFICE.

GEORGE L. BANKS, OF WALNUT PARK, CALIFORNIA.

AEROPLANE.

1,424,130.

Specification of Letters Patent. Patented July 25, 1922.

Application filed June 2, 1920. Serial No. 386,002.

To all whom it may concern:

Be it known that I, GEORGE L. BANKS, a citizen of the United States, residing at Walnut Park, in the county of Los Angeles and State of California, have invented new and useful Improvements in Aeroplanes, of which the following is a specification.

This invention relates to aeroplanes and has for its object the provision of a propeller construction wherein the propeller may be shifted from its normal position with its axis of rotation lying in a plane approximately parallel to the plane of the wings of the aeroplane to a position in which the plane of the axis of rotation of the propeller is angularly disposed relative to the plane of the wings. By this arrangement the climbing possibilities of an aeroplane may be greatly increased and the tendency of an aeroplane to nose dip may be overcome.

The invention will be readily understood from the following description of the accompanying drawings, in which

Figure 1 is a side elevation of an aeroplane constructed in accordance with the invention.

Fig. 2 is a top plan view of the same.

Fig. 3 is a longitudinal section on the line 3—3 of Fig. 2.

Fig. 4 is a transverse section on the line 4—4 of Fig. 3.

The aeroplane may comprise a usual or any preferred construction of body 1 having the rudder 2 and the wings 3 and 4 in superimposed normally substantially horizontal planes.

The central portions of the wings 3 and 4 are provided with openings 5 and 5' respectively, and the improved supporting mechanism for the propeller is mounted upon the lower plane 4 over the opening 5' therein. This supporting mechanism may include a frame 6 mounted upon the lower wing 4 and having the arcuate guideway 7 extending longitudinally of the aeroplane and from one side to the other of the opening 5' in an upwardly extending bow above the latter.

A similar arcuate cross brace 8 is secured to the guideway 7 and extends at substantially right angles thereto from one side to the other of the frame 6 over the opening 5'. A shaft 9 extends transversely of the aeroplane above the opening 5' and is, preferably, journaled at its respective ends in bearings 10 upon the frame 6. An arcuate

gear wheel 11 is free for rotation upon shaft 9, said gear wheel extending within the guideway 7. A radially extending sleeve 12 projects from the gear wheel 11 and is suitably secured to said gear wheel. The propeller shaft 13 is journaled in this sleeve and at its rear end is journaled in the hub 14 of the gear wheel 11.

A bevel pinion 15 is fixed for rotation with the propeller shaft adjacent the hub 14, and this bevel pinion meshes with a bevel gear wheel 16 fixed upon the shaft 9. The outer end of the propeller shaft projects beyond the sleeve 12 and is provided with a usual propeller 17 beyond the front of the body and wings of the aeroplane.

The driving connection for bevel gear 16 arranged to cause rotation of the propeller shaft and the propeller may include a shaft 18 journaled in a suitable bearing 19 within the body of the aeroplane and having a bevel pinion 20 meshing with bevel gear 16 and a bevel pinion 21 at its opposite end meshing with a bevel pinion 22 upon the main shaft 23 of the motor 24 of the aeroplane mounted within the body of the machine.

By this arrangement it will be seen that the propeller is adapted to be rotated irrespective of the position to which the gear wheel 11 and the propeller shaft are rotated upon the pivot formed by shaft 9. The gear wheel 11 is normally so positioned that the propeller shaft extends in a plane substantially parallel to the planes of the wings of the aeroplane as in the usual construction. But when it is desired to ascend in the aeroplane or when the latter has started a nose dip the gear wheel 11 and the propeller shaft carried thereby are adapted to be rotated with shaft 9 so that the propeller shaft will be tilted upwardly relative to its normal plane. This upward tilt of the propeller will cause a corresponding ascension of the aeroplane as will be readily understood. The propeller shaft and propeller are, preferably, arranged to be tilted in this manner from normal position, as shown in full lines in Fig. 1, into the position shown in dotted lines in Fig. 1 in which the propeller shaft extends upwardly substantially perpendicular to the planes of the aeroplane wings. In this position the propeller will be in axial alignment with the openings 5 and 5' in the wings of the aeroplane, and the rotation of the propeller will thus cause the air to be

forced through these openings and as a consequence the aeroplane will ascend at a steep incline.

The mechanism employed for causing rotation of gear wheel 11 is, preferably, manually controlled by the pilot of the machine and may include a shaft 28 journaled in suitable bearings 29 formed upon guideway 7, said shaft having a worm gear 30 thereon meshing with the gear of gear wheel 11 which consists of a co-operating worm gear 31. The end of shaft 28 extends to a point adjacent the pilot's seat and is provided with actuating means shown as a hand wheel 32. It will be seen that the construction thus provided forms self-locking means whereby the gear wheel 11 will remain in adjusted positions, said gear wheel being adapted to be shifted upon the axis formed by shaft 9 to any desired position for causing desired upward tilt of the propeller. The tendency of an aeroplane to nose dip may thus be overcome by the tilting of the propeller, as thus described, and such tilting of the propeller will also permit of making an ascension at a steep inclination when so desired.

While I have described the invention as applied to an aeroplane having means arranged in two superimposed planes it will be apparent that the invention is applicable to a machine having its wings arranged in any number of superimposed planes. Thus, for example, in a monoplane type of machine the supporting apparatus for the tiltable propeller would be mounted directly upon the body of the machine and the single wing of the machine would be provided with an opening above which the propeller would extend when tilted into its uppermost position. When the invention is applied to the type of machine having more than two superimposed wings it will be understood that all of the wings above the supporting means for the tiltable propeller will be provided with central openings, and the propeller, when tilted to its uppermost position, will be arranged in alignment with said openings and above the uppermost wing.

Various changes may be made without de-

parting from the spirit of the invention as claimed.

What is claimed is:

1. An aeroplane having a wing provided with an opening that extends to the forward edge of said wing, a gear wheel pivoted on the body of the aeroplane below the center of said opening and occupying a plane substantially perpendicular to the plane occupied by said wing, a propeller shaft carried by said gear wheel and extending radially thereof, a propeller carried by said shaft, a pinion concentrically mounted with relation to said gear wheel, a pinion upon the propeller shaft with which the first mentioned pinion engages, an engine having a driving connection with the first mentioned pinion for rotating said propeller shaft, means for rotating said gear wheel to shift the propeller from its normal position in a plane perpendicular to the wing to a plane substantially parallel with said wing, the shaft of the propeller being of sufficient length to permit the propeller to occupy a position above the wing when said propeller shaft is shifted into a vertical position, and the opening in the wing having a diameter greater than the length of the combined propeller blades.

2. In an aeroplane, a wing provided with a centrally arranged opening, one side of which extends to the forward edge of said wing, an arcuate member pivotally mounted on the body of the aeroplane below said opening, means for shifting said arcuate member through a vertical plane, a propeller shaft carried by said arcuate member, means for driving said propeller shaft, a propeller on the forward end of said shaft, the length of which propeller shaft permits the propeller to occupy a position above the opening in the wing when said shaft is shifted into a vertical position, and the opening in said wing having a diameter greater than the combined length of the propeller blades.

In testimony whereof I have signed my name to this specification.

GEORGE L. BANKS.
